[57] CLAIM

The ornamental design for a vehicle engine attached food heating container, as shown and described.

DESCRIPTION

FIG. 1 is a perspective view of a vehicle engine attached food heating container showing my new design; FIG. 2 is a front elevational view thereof, the rear view being a mirror image;

FIG. 3 is an end elevational view thereof, the opposite end being a mirror image;

FIG. 4 is a top plan view thereof; and,

FIG. 5 is a bottom view thereof.

FIG.1.

FIG. 2.

FIG. 4.

FIG. 3.

FIG. 5.
